APPARATUS FOR CLEANING DISHES PRIOR
TO WASHING HAVING MEANS FOR SEP-
ARATING TABLEWARE AND GARBAGERussell M. Carson, Kansas City, Mo., assignor to
Russell M. Carson and Ethel Hohl, both of
Kansas City, Mo., trustees

Application February 7, 1949, Serial No. 75,026

3 Claims. (Cl. 134—104)

1

This invention relates to table ware scrapping and salvaging machines in the nature of those disclosed in United States Letters Patent No. 2,400,879, issued May 28, 1946, to F. T. Hilliker; and the primary aim of this invention is to improve the machine disclosed in said Letters Patent by providing equipment capable of separating table ware that might accidentally be washed from dishes with the garbage removed therefrom in a more efficient manner and through the employment of less expensive machines than those heretofore utilized for the purpose.

Another important object of this invention is to provide apparatus for cleaning dishes prior to washing, which apparatus has means for separating table ware from the garbage if such table ware is accidentally flushed from the dishes being cleaned, which apparatus utilizes an uniquely-formed, table-like basin constituting the top thereof and into which the flushing water and garbage is emptied.

Yet further aims of the invention are to provide apparatus of the aforementioned character wherein the specially-formed, table-like basin forming the top has an outlet port near the marginal edge of the basin thereof, so disposed as to cause fluids and entrained solids passing therethrough to be traveling in an upward direction, all to accomplish the result of separating relatively heavy table ware directly in the said basin through the action of gravity; and wherein the aforesaid outlet port is protected by a downwardly and inwardly-angled deflector lip to cooperate with the port and the remaining part of the basin to preclude accidental escape of table ware, in the event any should be washed into the basin from dishes being treated.

Other aims of the invention will appear during the course of the following specification, referring to the accompanying drawing, wherein:

Fig. 1 is a top plan view of apparatus for cleaning dishes prior to washing having means for separating table ware and garbage, and embodying my invention.

Fig. 2 is a perspective view of the basin forming a part of the apparatus but entirely removed from association with the remaining elements of the machine.

Fig. 3 is a side elevational view of the apparatus, parts being broken away for clearness; and,

Fig. 4 is a similar elevational view of another side of the apparatus with portions of the ma-

chine eliminated to reveal normally-hidden elements.

The form of apparatus chosen for illustration embodies the preferred manner of constructing equipment capable of performing the broad objects of the invention. In said preferred form, the numeral 10 designates a reservoir of generally cylindrical shape but with an open top, closed by a specially-formed basin broadly designated by the numeral 12. Reservoir 10 has a water inlet pipe 14 in communication therewith, which pipe is joined by pipes 16 and 18 connected to sources of hot and cold water, respectively.

15 Thus, through manipulation of valves 20 and 22 interposed in pipes 16 and 18, respectively, the flow of hot and cold water may be regulated, and the temperature of water passing into reservoir 10 by pipe 14 determined and maintained at the desired degree. It has been found that tepid water having a temperature of substantially 105° F. is most desirable where garbage is washed and reashed to remove fats therefrom. More will be hereinafter set forth with 20 respect to the advantage of using tepid water having the temperature just stated.

25 Overflow pipe 24 extending upwardly into reservoir 10 from the bottom thereof terminates in an open end substantially midway between the bottom and top of tank 10. This overflow pipe 24 is connected to a drain or another conduit 26 leading through a grease trap and thence to a drain. The grease trap need not be illustrated, for they are well-known in the art and quite conventional. As water passes through these grease traps, the entrained grease and oils are removed therefrom, and the water free of grease passes into the drain.

30 A fluid feed pipe 28 extending upwardly along one side of reservoir 10 terminates as shown in Fig. 4 and, when water is pumped upwardly through this said pipe 28, it will pass through a path of travel illustrated by the numeral 30. This fluid feed pipe is in communication with 35 a pump 32 which, in turn, is driven by an electric motor 34 mounted upon reservoir 10, as shown in Fig. 3.

35 Pump 32 communicates directly with the interior of reservoir 10, and water from the reservoir is withdrawn by pump 32 and forced upwardly through fluid pipe 28 to assume an arcuate path of travel convenient for the operator when dishes are being cleaned by the force of the vat of water 30.

50 Basin 12 closes the open end of reservoir 10,

and this basin is of special and important form. Its marginal, annular flange 36 is provided with openings 38 in register with similar openings in outturned flange 40 on reservoir 10; and bolts or analogous fastening elements 42 pass through the registered openings to maintain the reservoir 10 in an operative position.

An opening 44 through basin 12 accommodates the slightly arched end 46 of pipe 28 when the basin 12 is in the position illustrated in Figs. 1 and 4. Basin 12 is concave to afford a cavity 48 into which water from pipe 28 is directed after it strikes the dishes being treated to remove garbage therefrom.

The stream of fluid 30 emanating from pipe 28 and created by the force of pump 32 falls upon the inner face of basin 12 at a point to one side of the vertical axis of the basin; and the impingement of the stream of water upon the curved surface of the basin within cavity 48 establishes a force sufficient to carry particles of garbage and waste foods upwardly through outlet port 50 formed through the bottom of basin 12 to one side of its center. This outlet port is rectilinear in longitudinal shape and comparatively narrow, as clearly illustrated in Figs. 1, 2 and 4.

The port is overhung by a deflector lip 52, the upper surface whereof is disposed at an angle; and this deflector lip 52 precludes the accidental passage of any solids through port 50. In fact, solids cannot pass through this port 50 without the assistance of the fluid 30 passing through a path illustrated in Fig. 4.

The depth of cavity 48 formed by basin 12 is sufficient to retain any silverware that may accidentally be carried into the basin when the garbage is washed from table ware and, as the operator manipulates the dishes, any silverware remaining in basin 12 may be lifted therefrom periodically and at convenient times. Thus, assurance is always present that accidentally-dropped silverware will not pass to a point where the same may not be quickly recovered and returned to use.

A foraminous basket 54 is hung within reservoir 10 to one side of feed pipe 28 and overflow pipe 24. This basket is hung upon an annular shoulder 56 within reservoir 10 and may be lifted from the reservoir after basin 12 has been taken from its normal position. This basket catches particles of garbage of a size greater than might pass through the openings in the mesh from which the basket is formed.

During the operation of the apparatus above described and shown in the accompanying drawing, ware from the table such as plates and other dishes that are to be washed, and which carry waste food, are passed beneath the stream of water 30 which is not in the nature of a spray but is a compacted, arcuate column capable of flushing garbage from the table ware being treated.

When the column of water 30 strikes the inner arcuate face of basin 12 to one side of the axis of the cavity 48, a force toward outlet port 50 is exerted and particles of garbage are entrained within the escaping water by floatation or otherwise and motivated through the outlet port to a position within basket 54. The water escapes from overflow pipe 24 when the level thereof reaches the open end of said pipe, and the speed with which the water passes out through overflow pipe 24 is obviously governed by the amount of

"make up" water or fresh water that is introduced into reservoir 10 through pipe 14.

In practice, from 1 to 1½ gallons of water should escape from reservoir 10 through overflow pipe 24 when the thermal condition of the water introduced is such as to maintain a temperature of 105° F., throughout the mass of water within reservoir 10 and, obviously, that which is being pumped through pipe 28 to create the column 30. Such method of manipulating the apparatus will result in an efficient recovery of fats, particularly because all of the garbage will be washed clean and freed of its fatty content, resulting in the elimination of objectionable odors.

15 The position of deflector lip 52 and outlet port 50, with respect to the arcuate column of water 30, is as clearly shown in Fig. 4; and such disposition is important, because of the resulting advantageous function due to the placement of 20 parts as above specified.

From the foregoing, it will be observed that garbage and table ware accidentally washed from dishes will be effectively separated within basin 12 without the employment of any other part.

25 Garbage substantially free from fats will be collected in basket 54, where the temperature and volume of the water passing through the machine is maintained as aforesaid; and, because of such novel features, the apparatus illustrated is capable of producing better results than have heretofore been accomplished by machines with a larger number of parts and more complicated mechanisms.

Obviously, apparatus having physical characteristics different from those illustrated and described might be made without departing from the spirit of the invention and scope of the appended claims.

Having thus described my invention, what I 40 claim as new and desire to secure by Letters Patent is:

1. In a dish cleaning and tableware salvaging machine, the combination of an open top liquid basin having an arcuate, horizontal, uppermost edge and an elongated deflector plate mounted within the basin on one side of the vertical axis of the basin and having a transverse axis extending inwardly and downwardly from a horizontal plane coincident with said edge, said deflector plate having a lowermost horizontal edge between said plane and the bottom of the basin, that part of the basin below said deflector plate and above a horizontal plane through said lowermost edge of the deflector plate being entirely cut away, presenting an elongated overflow edge in the basin; and a liquid feed pipe having an outlet end disposed at an angle upwardly and inwardly toward the basin to direct liquid thereinto and on that side of the vertical axis of the basin opposite to the deflector plate, said basin comprising a segment of a hollow sphere whereby to develop a liquid current in the basin directed upwardly and outwardly therefrom toward and over said overflow edge.

65 2. In a dish cleaning and tableware salvaging machine, the combination of an open top liquid basin having an arcuate, horizontal, uppermost edge and an elongated deflector plate mounted within the basin on one side of the vertical axis of the basin and having a transverse axis extending inwardly and downwardly from a horizontal plane coincident with said edge, said deflector plate having a lowermost horizontal edge between said plane and the bottom of the basin, that part of the basin below said deflector plate

and above a horizontal plane through said lowermost edge of the deflector plate being entirely cut away, presenting an elongated overflow edge in the basin; and a liquid feed pipe having an outlet end disposed at an angle upwardly and inwardly toward the basin to direct liquid thereinto and on that side of the vertical axis of the basin opposite to the deflector plate, said basin comprising a segment of a hollow sphere whereby to develop a liquid current in the basin directed upwardly and outwardly therefrom toward and over said overflow edge, said overflow edge being longitudinally arcuate and within said plane through the lowermost edge of the deflector plate, whereby all garbage floating in the liquid with the basin will readily pass over said overflow edge as heavier articles such as silverware settle to the bottom of the basin.

3. In a dish cleaning and tableware salvaging machine, the combination of an open top liquid basin having an arcuate, horizontal, uppermost edge and an elongated deflector plate mounted within the basin on one side of the vertical axis of the basin and having a transverse axis extending inwardly and downwardly from a horizontal plane coincident with said edge, said deflector plate having a lowermost horizontal edge between said plane and the bottom of the basin, that part of the basin below said deflector plate and above

a horizontal plane through said lowermost edge of the deflector plate being entirely cut away, presenting an elongated overflow edge in the basin; and a liquid feed pipe having an outlet end disposed at an angle upwardly and inwardly toward the basin to direct liquid thereinto and on that side of the vertical axis of the basin opposite to the deflector plate, said basin comprising a segment of a hollow sphere whereby to develop a liquid current in the basin directed upwardly and outwardly therefrom toward and over said overflow edge; and a flat, horizontal shelf connecting the deflector plate at the uppermost edge of the latter with said arcuate edge of the basin, 15 said pipe extending through said shelf.
